5/636, 637, 640, 652–655, 655.3, 655.9,
5/419, 420, 731; D21/809

FIG. 6 is a left view of an infant support pillow; and,

See application file for complete search history.

FIG. 7 is a right view of an infant support pillow.

(56) **References Cited**

The claimed pillow is for positioning an infant while it drinks from a bottle. The pillow provides a firm base, an arm rest, inserts to conform to the baby, and a contoured pillow for inclining the infant to prevent milk from draining into the infant's ears, aiding in digestion, and preventing infections. The pillow is universal for left- or right-handed feeding.
